CLAIM

The ornamental design for putter golf club head, as shown and described.

DESCRIPTION

FIG. 1 is a perspective top plan view of a putter golf club head showing my design;

FIG. 2 is a top plan view thereof;

FIG. 3 is a bottom plan view thereof;

FIG. 4 is a toe end view thereof;

FIG. 5 is a heel end view thereof;

FIG. 6 is a front elevation view thereof; and,

FIG. 7 is a rear elevational plan thereof.

The broken lines shown form no part of the claimed design.
